UNITED STATES PATENT OFFICE.

DENNIS F. VAN LIEW, OF AURORA, ILLINOIS.

CAR-DOOR HANGER.

SPECIFICATION forming part of Letters Patent No. 245,035, dated August 2, 1881.

Application filed May 20, 1881. (No model.)

To all whom it may concern:

Be it known that I, DENNIS F. VAN LIEW, of Aurora, in the county of Kane and State of Illinois, have invented certain new and useful 5 Improvements in Car-Door Hangers, of which the following is a specification.

This invention relates to the hangers used upon freight-car doors; and it constitutes an improvement upon the construction of hangers set forth in the patent to Alexander N. Monteer, reissued to myself and said Monteer, April 27, 1880.

The invention is designed to render the operation of opening and closing the door as near frictionless as possible, and also to render the door so tight that it will perfectly exclude sparks and water.

The primary feature of my improved construction consists in housing each of the rollers or balls whereon the door rests in elongated sockets substantially equal in length to the distance required to be traveled by the ball in the operation of the door.

By this improvement I do away with the 25 friction between the ball and the pushing side of its holding-socket, and the benefit of it is especially felt in starting the door.

The other portions of my invention relate to certain details of construction, which are fully 30 explained hereinafter.

In the drawings, Figure 1 is an exterior view of a car and door to which my improvements have been applied. Fig. 2 is an enlarged vertical section of the door-hanging devices. Figs. 35 3 and 4 are longitudinal sections of the parts shown in Fig. 2, Fig. 3 being a vertical section upon the line *x x*, and Fig. 4 a horizontal section on the line *y y*.

In said drawings, A represents the car-side, 40 A' the car-roof, and B the car-door. Suspended from the car-front, and secured by bolts or lag-screws, is a metal carrier, C, curved in cross-section, so as to afford bearings at right angles to each other—that is, at side and bottom to the roller-balls D. In length it extends the width of the door and about one-half the distance traveled by it in opening, this additional length being located upon the side toward which the door is moved in opening. 45 50 This carrier is thus made to support and form

a travel-way for the rollers or balls D, and confines them upon the outer side.

Attached to the door by rivets *b* is a metal piece, E, shaped similarly to the carrier, but reversed in position, so as to rest upon the 55 balls. It extends from side to side of the door. This piece I call the "hanger." It forms the other side and the top bearings for the balls. At each end and at the center of this hanger are cross-projections *e e' e''*, which divide the 60 inclosed space between the carrier and hanger into two elongated sockets or receptacles, in each of which is placed a ball, D. As the balls move through but one-half the distance traveled by the door I make these sockets to correspond as near as may be with the distance traveled by the ball. In this way the ball is kept from contact with the socket ends at all 65 times during the sliding of the door, and a great deal of friction is avoided. As shown in 70 the drawings, the door is closed, in which position the balls occupy the right ends of their respective inclosures; but when the door is opened the balls will move to the points indicated in dotted lines, and at the left ends of 75 the sockets.

To support the left edge of the door when it is closed I provide the carrier at that end with a sloping support, *c*, upon the surface of which the end stop, *e*, may ride, whereby the door is 80 kept level, and the weight and consequent wear while the car is running is taken in part from the balls. By making the support *c* sufficiently high the sustaining of the door at the two corners may be made a matter of certainty; and 85 for the same purpose I also support the right edge of the door, when open, upon a sloping-surfaced piece, *c'*, secured to the car-side, and adjusted to receive the other end stop, *e''*.

When the door is closed it is important that 90 the right or free edge thereof be made to hug the car as closely as possible, because no such rabbet or groove joint can be formed therewith as with the other edge. To accomplish this I provide the interior of the carrier C, opposite the point occupied by the right-hand ball D, with an inward projection or thickening, *c''*, which crowds the ball, and through it the door, closely up against the car-side. 95

The construction shown shuts out sparks 100

and rain very perfectly, and much more perfectly than when the door is hung by the hangers shown in said Monteer patent. Lateral strains do not affect the operation of this door, 15 as they do in other methods of construction. Being confined between the flat surfaces at top, bottom, and sides, the balls roll between such of the opposing surfaces as exert the greatest pressure thereon. They revolve in all directions, so as to wear evenly upon all sides and preserve their spherical form.

Car-doors are often subjected to an outward lateral strain from the freight confined within. In such cases with but the old rolling devices, 15 such as wheels, no relief is furnished from the friction therefrom; but it will be apparent that the balls in my device afford relief from friction in whatever direction upon them it may come, whether vertically or horizontally. Of course, unnecessary friction between the balls and the sides of their sockets should be avoided; and hence, except at the thickening c^2 , I leave a free space between them and said sides, 20 as shown at m . The adjacent parts of the hanger and carrier should also be at a sufficient remove to prevent actual contact, so that all lateral pressure from either side will be received and borne by the balls.

A stop, d , at the right end of the carrier 25 serves to prevent the ball from slipping out of

its socket. Ordinary lateral supports are used to retain the bottom end of the door. The support c may be made separate from the carrier, like the support c' , if thought best.

While I have shown two roller-balls, I do not 35 wish to confine myself to that number, as a single ball might be employed, or a larger number than two might be used by elongating the carriers and increasing the number of sockets. I prefer, however, to employ two. 40

I claim—

1. The combination, with the car and its door, of the ball or balls confined in sockets equal, or essentially equal, in length to the distance traveled by the balls in the operation of 45 the door, substantially as specified.

2. The combination, with the door sliding upon rollers or balls confined in long sockets, substantially as set forth, of the supports c c' , 50 one or both, for supporting the edges of the door, as specified.

3. The combination of the door and its supporting-rollers with the projection c^2 upon the inner side of the carrier for forcing the door against the car-side, substantially as specified. 55

DENNIS F. VAN LIEW.
